WILLIAM E. BEACH, OF RIVERSIDE, ILLINOIS

METHOD AND MACHINE FOR USE IN PAPER MAKING INDUSTRY

Application filed November 16, 1931. Serial No. 575,395.

The invention relates to a method and means for preventing dehydration of material such as wood fibre or other stock to maintain same in a condition facilitating circulation thereof.

The invention has among its prime objects the provision of a method of handling slush stock such as is employed in the paper making industry in a manner so that a portion thereof is maintained in a more or less liquid condition by preventing dehydration thereof.

The invention has among its principal objects the provision of a method of handling slush stock which will prevent dehydration and retain the material in a fluid or semi-fluid condition so that circulation thereof is facilitated and intermittent operation of the device made possible instead of requiring constant operation of the device to prevent dehydration.

It is an object of the invention to provide a machine which may be operated for a prescribed period of time to transfer slush stock from a slush tank or reservoir to beaters employed in the paper making art and to combine with a structure such as that just referred to, means whereby when the operating mechanism employed to cause circulation of the stock is brought to a rest, a portion of the slush stock will be trapped in a manner to prevent dehydration and maintain same in a liquid condition or in a condition in which it may be readily circulated to the beaters above referred to.

The invention also has as an object the provision of an electrically operated device which may be remotely controlled by the operator to cause the device to function to create circulation and to also be brought to a condition of rest with certain elements of the structure arranged to trap a certain quantity of the slush stock in the manner and for the purpose hereinabove referred to.

The invention has these and other objects, all of which will be explained and more readily understood when read in conjunction with the accompanying drawings which illustrate one arrangement for accomplishing the various objects and the method hereinafter to be explained, it being obvious that changes and

modifications may be resorted to without departing from the spirit of the appended claims forming a part hereof.

In the drawings, Fig. 1 is an elevation illustrating a mechanism for accomplishing the objects and method hereinbefore referred to;

Fig. 2 is a view of a circuit diagrammatically illustrating certain of the elements employed in the structure shown in Fig. 1;

Fig. 3 is a side view of a portion of a mechanism for operating a valve employed in the structure;

Fig. 4 is a plan view of the structure shown in Fig. 3;

Fig. 5 is an end view of the structure shown in Fig. 4;

Fig. 6 is a plan view of a switch actuating mechanism operable by the structure illustrated in Figs. 3 and 4;

Figs. 7 and 8 respectively are sections taken on lines 7-7 and 8-8 of Fig. 6;

Fig. 9 is an end view of the structure shown in Fig. 6;

Fig. 10 is a central section through a valve employed in the structure illustrating certain portions of the mechanism disclosed in Figs. 3 and 4 combined therewith for actuating the valve; and

Figs. 11 and 12 are sectional views of a portion of a valve shown in Fig. 10 showing same in respectively open and closed positions.

The embodiment of the invention illustrated in Fig. 1 contemplates the utilization of a stock tank generally designated 11 and a beater generally designated 12 which are connected with each other through the agency of a pipe line generally designated 13. A motor 14 is employed for operating a pump 15 for causing circulation of slush stock from the stock tank 11 through the pipe line 13 to the tank of the beater generally designated 12. A control valve generally designated 16 is located in the pipe line 13 between the pump 15 and the outlet 17 of the pipe line, it being understood that one or more beaters 12 are arranged relatively to the pipe line 13 so that slush stock may be deposited therein from spouts such as that designated 17 having a valve 23. The valve 16 is motor-driven

and to this end, the motor 18 is employed, the motor shaft having a worm 19 which meshes with a worm wheel 20 secured to the shaft 21 of the valve 16.

5 A brake mechanism generally designated 22 is employed to hold the valve 16 in either an open or closed position. This brake mechanism includes a brake drum 22' and a lever mechanism, however, this mechanism may be 10 of any other desired construction. It may be here stated that the pipe line 13 together with the goose neck spouts such as 17 and the valve generally designated 16, cooperate to provide what might be termed a trap in which a suitable amount of slush stock which may be of a liquid or semi-liquid consistency is trapped to maintain it in a liquid or semi-liquid condition or against dehydration.

20 Machines of the character above referred to prior to my invention are designed to prevent dehydration by constant operation of the machine and constant circulation of the stock. In the construction herein shown, periodic operation of the device and periodic 25 circulation of the slush stock from the stock tank to the beaters may be accomplished, this being made possible by virtue of the fact that a portion of the material in the circulatory system is maintained in a condition permitting 30 free circulation thereof, thus reducing the cost of operation of the device and naturally adding to the longevity of the structure.

35 In the operation of the structure illustrated in Fig. 1, the motor 14 which operates the pump 15 and the motor 18 which actuates the valve generally designated 16 is started through manipulation of the remote control switch designated A which causes actuation 40 of the motors 14 and 18 and causes the valve 16 to be opened and the slush stock to be transferred from the stock tank to the beater tanks for any desired period of time. The structure is such that manipulation of the switch 45 A again brings the device to a rest with the valve 16 in a closed condition so as to trap a certain quantity of the slush stock in the pipe line 13.

50 The shaft of the valve 16 carries devices such as are most clearly shown in Figs. 6, 7, 8 and 9 which are designed to respectively operate a valve motor cut-out switch generally designated B, a pump cut-out switch generally designated C and a pump starting switch 55 generally designated E, all clearly shown in the diagrammatic view designated Fig. 2.

60 The operation of the device will now be described with particular reference to Fig. 2 with the valve 16 in a closed position and the pump and other devices in an inoperative condition. To cause the device to function and create circulation, the operator manipulates the remote control switch A which completes a circuit including the conductor L¹ to terminal F, conductor T through the switch

A, conductor G to terminal H of starter box generally designated I, through the coil of a solenoid J, to terminal J¹ and conductor L³. Closing of this circuit energizes the solenoid J and causes the motor switches diagrammatically illustrated and designated K and also the interlocking switch L to be closed and maintained in this condition. Upon release of the switch A, the circuit just explained is broken, however, by virtue of the interlock L, another circuit is set up which includes the conductor L¹, terminal M, terminal M¹, conductor M² through the normally closed switch B through conductor M³ to terminal H in starting box I through the coil of the solenoid J, through terminal J¹ and line L³, it being manifest that while the solenoid J is energized, the switches K and L will be maintained in a closed condition which will cause current to travel through conductors L¹, L² and L³ through said switches to motor contacts O which will cause actuation of the valve motor 18 which will thus, through the agency of the worm and worm wheel respectively designated 19 and 20 cause the valve 90 to be rotated from its previous closed position to an open position also causing rotation of the various elements shown in detail in Figs. 6, 7, 8 and 9 which are secured to the shaft of the valve 16.

95 It will be noted that the solenoid coil of the magnetic brake generally designated P is connected through conductors P¹ and P² with conductors extending to the motor terminals O from those switches K which are 100 respectively connected with the conductors generally designated L¹ and L² which will energize said solenoid coil and cause same to release the brake shoes U of the brake and thereby allow free rotation of the valve motor and the elements actuated thereby. As the valve is rotated by its motor 18 from a closed to an open position, it is necessary that the valve motor and the valve be brought to a position of rest. This is accomplished 105 through the medium of the anti-friction rollers 24 which are carried by a rotatable element 38 directly connected to worm gear 20 mounted upon the shaft 21 of the valve, which 110 engage the cam 30 of the valve motor cut-out switch B to open said switch. Opening of the switch B causes the previously established circuit including the conductor L¹, terminals M and M¹, conductors M², M³, H, solenoid J, terminal J¹ and conductor L³ to be 115 broken which deenergizes the solenoid J and thus releases switch K and the interlocking switch designated L. With the switches K in an open condition, the motor 18 is brought to a rest. The magnetic brake designated P is simultaneously deenergized, which permits the spring 25 shown in Figs. 4 and 5 to act to apply the brakes U to brake drum 22' and thus hold the valve in an open position. Rotation of the valve 16 to open posi- 120

tion causes a roller 26 carried by the frame 27 to engage the plunger 28 causing depression and engagement thereof with the push button of the pump starting switch generally designated E closing this switch.

The mechanism just referred to is clearly shown in Fig. 9 from which it can be seen that the switch E is momentarily closed when depressed by the roller 26 which establishes a circuit including the conductor L¹, terminal Q of the pump motor starter box X, conductor Q¹ through switch E, conductor Q², through the coil of solenoid Q³ to conductor L³ causing the pump motor switches R and the interlocking switch S to be closed, this circuit being broken immediately when the roller 26 passes beyond the plunger 28 which allows the switch E to assume its normally open position.

The interlocking switch S being closed by operation of the switch E, a circuit is established through conductor L¹ to terminal R¹ through the switch S, conductor R² switch C, across to one terminal of switch E through conductor Q², through solenoid Q³, through said solenoid to conductor L³. By virtue of the fact that the switches R are at this time closed, current will pass from conductors L¹, L² and L³ through the switches R to the terminals R³ of the pump motor 14 which actuates the motor and pump for the entire period that the valve 16 is held open. The pump motor is actuated and remains in operation until the operator again actuates the switch A which will again close this switch and establish a circuit through the conductor L¹ to terminal F, through conductor T, switch A, conductor G to terminal H, through the solenoid J and conductor L³. This again closes the switches K and L, however, as soon as the operator releases the switch A, this opens the switch and a circuit is established through conductor L¹ to terminal M, through interlocking switch L in starting box I, through terminal M¹, conductor M², switch B, conductor M³, through terminal H, solenoid J to terminal J¹ and conductor L³ which maintains the coil of the solenoid energized which, in turn, causes the switches K and the interlocking switch L to be maintained in a closed condition. The valve motor 14 is thus caused to be actuated to move the valve to a closed position, this being accomplished by virtue of the fact that a circuit is established including conductors L¹, L² and L³ through switches K to terminals O of the valve motor 18, and by virtue of the fact that the magnetic brake P is connected with conductors leading to the terminals O of the valve motor causes the magnetic brake to release the holding action of the brake shoes U allowing free rotation or movement of the valve from an open to a closed position, which movement is approximately ninety degrees (90°).

By again referring to Fig. 7, it will be seen that as the valve is rotated through the worm and worm wheel respectively designated 19 and 20, one of the rollers 24 mounted for rotation with the shaft 21 of the motor engages the plunger 30 which actuates the switch B, opening the switch and causing the solenoid J to become deenergized, allowing the switches K and the interlocking switch L to open which breaks the circuit to the valve actuating motor 18, again deenergizing the magnetic brake generally designated P, allowing the spring 25 thereof and other elements connected therewith to function to hold the valve in a closed position. During this rotation of the valve to a closed position, one of the rollers 31 (Fig. 8) engages the plunger 32 of the switch C and opens said switch. This breaks the circuit including the conductors L¹, R¹, R² and Q² which deenergizes the solenoid Q³. Deenergization of the solenoid Q³ releases the motor pump switches R and the interlocking switch S which breaks the circuit including the conductors L¹, L², and L³ and the conductors leading to the terminals R³ of the pump motor 14 causing the pump motor 14 to be rendered inoperative. Thus, the valve 16 is maintained in its inoperative position to prevent pumping of slush stock through the pipe line 13. Manifestly, a quantity of the slush stock is trapped in the pipe line 13 above the valve 16 which will thus maintain the stock in a fluid or semi-fluid state or in a condition in which it may be readily forced through the pipe line upon subsequent operation of the pump 14 when the valve 16 is again opened. It is evident that since the stock is prevented against dehydration and is maintained in a fluid or semi-fluid state, same may upon a subsequent operation of the device, be discharged from the pipe line, which results in permitting periodic instead of constant operation of the device with a consequent reduction in cost of operation.

By again referring to Figs. 8 and 9, it will be noted that the rollers respectively designated 31 and 26 are mounted upon frames such as those designated 27 in Figs. 8 and 9. Since these frames are identical in construction with each other, an explanation of one will suffice for an understanding of both. It will be noted by reference to the structure of the frame 27 that same is directly connected for rotation with frame 38, which in turn is directly connected to worm wheel 20 mounted on the valve shaft 21. The frames 27 are provided with a hub 33 and radial arms respectively designated 34 and 35, the arms being provided with the arcuate slots 36 which are provided to receive a cap or set screw 37 which are threaded into said frame 38. This structure allows of adjustment of the frames 27 about the axis of the shaft 21 to thereby arrange the rollers 24, 26 and 31 in various

positions of angularity to thus permit the same to function in proper time to accomplish the various objects hereinabove referred to.

5. By referring to Figs. 10, 11 and 12, it will be seen that the valve generally designated 16 contemplates the utilization of a valve rotatably mounted in a casing, rotation being accomplished through the agency of the 10 worm wheel 20. By referring to Figs. 11 and 12, it will be noted that the valve per se which is designated 39 has cutting edges such as 40—40 which are provided to cut or shear any of the stock which might become lodged 15 between the valve per se 39 and the casing of the valve. From the foregoing it is evident that operation of the motor 14 causes slush stock to be pumped and circulated through the pipe line 13 and delivered from the stock 20 tank 11 to the various beater chests 12, it being understood that this motor is constantly operated to cause circulation of the slush stock in the manner just referred to after the remote control switch A has been actuated to 25 cause the valve to be opened and that the valve remains in this open condition until the remote control switch A is again actuated to rotate the valve 16 to a closed position which traps a portion of the slush stock within 30 the pipe line 13 and maintains same in a fluid or semi-fluid condition or in a condition in which it is capable of being discharged from the pipe line resulting in the elimination of the necessity of constant operation of the machine to prevent dehydration.

Having thus described the invention, what I claim as new and desire to cover by Letters Patent is:

1. In a machine for handling slush stock 40 and preventing dehydration, the combination of a pair of receptacles, a tubular connection between said receptacles, whereby said slush stock may be transferred from one receptacle to the other, means for controlling transfer 45 of stock from one receptacle to the other and retaining an amount of said stock in an inert fluid condition in said tubular connection.

2. In a device for handling slush stock comprised of means for periodically circulating 50 said stock through a circulatory system and including means for retaining a portion of said stock in the circulatory system of said device in a condition for subsequent circulation.

3. The method of handling slush stock and preventing dehydration thereof which consists in circulating and transferring said stock and upon cessation of circulation trapping 60 a portion of said stock in the circulatory system and thus maintaining said stock in a condition substantially corresponding to its condition when circulated.

4. In a machine for handling slush stock and preventing dehydration thereof, the combination with a source of supply, means con-

nected with said source of supply providing a discharge for said stock from said source, and means for preventing dehydration including a trap located in said means between said source and one end of the discharge. 70

5. In a machine for handling slush stock and preventing dehydration thereof, the combination of a stock tank, a beater tank and a pipe line connecting said tanks, means for forcing stock from said stock tank to said beater tank, a valve in said pipe line, said valve providing means for preventing return of stock contained in said line to said stock tank, thereby maintaining said stock in a fluid condition in said line for subsequent discharge therefrom. 75

6. In a machine for handling slush stock and preventing dehydration thereof, the combination with a source of supply, means connected with said source of supply for transferring said stock from said source, a receptacle into which said stock is discharged from said means, and means in said first mentioned means for trapping a quantity of said stock 80 by said source and said receptacle. 85

7. In a machine for handling slush stock and preventing dehydration thereof, the combination of a stock tank, a beater tank and a pipe line connecting said tanks, means for forcing stock from said stock tank to said beater tank, a valve at the discharge of said pipe line, said valve providing an element of means for assisting to prevent dehydration and circulation of stock contained in said line between said valve and said stock tank. 90

8. In a machine for handling slush stock and preventing dehydration thereof, the combination of a stock tank, a beater and a pipe line connecting said tanks, and mechanism for intermittently transferring stock from said stock tank to the beater, and means whereby a quantity of said slush stock in said pipe line is maintained in an inert fluid state during the period of rest of said intermittent 105 operable mechanism. 110

9. In a machine for handling slush stock and preventing dehydration thereof, the combination of a stock tank and a beater with a pipe line connecting said tank and beater, mechanism for transferring stock from said stock tank to the beater, and a trap in said pipe line for trapping a quantity of slush stock in said line and maintaining said stock in an inert fluid state. 115

10. In a machine for handling slush stock and preventing dehydration thereof, the combination of a stock tank and a beater with a pipe line connecting said tank and beater, a valve in said pipe line, a pump connected with said line to transfer said stock from the tank to the beater, a motor for actuating said valve and a motor for actuating said pump, said valve providing means for preventing return of stock to said stock tank and trapping a quantity of said stock in said line and 120

- maintaining said stock in a condition for transfer thereof from the tank to the beater.
11. The method of transferring and maintaining slush stock in a substantially liquid condition which consists in circulating said stock from a tank to a beater, ceasing circulation and trapping a portion of said stock in the circulatory system and maintaining same therein in a condition for circulation.
- 10 12. The method of transferring and maintaining slush stock in a substantially liquid condition which consists in circulating said stock from a tank and supplying said stock to another receptacle, ceasing circulation and trapping a portion of said stock between said tank and receptacle when said receptacle has been supplied to thereby maintain said trapped stock in a condition for circulation to said receptacle.
- 20 13. The method of transferring and maintaining slush stock in a substantially liquid condition which consists in circulating said stock from a supply tank to a receiving receptacle, ceasing circulation and preventing flow 25 of said stock to said supply tank to thereby trap a portion of said stock between said tank and receptacle and maintain said portion in a condition for circulation to said receiving receptacle.

14. In a machine for transferring and maintaining slush stock in a substantially liquid condition, said device including a tank and receptacles, and a pipe line connecting said tank and receptacles, means for causing circulation of said stock from said tank to the receptacle, means for arresting said circulating means, a valve in said pipe line, means for closing said valve, said circulating means being brought to a rest with said valve in said last mentioned condition to thereby trap a portion of said material in the pipe line and maintain said portion of said material in a condition for circulation.

15. In a machine for transferring and maintaining slush stock in substantially liquid condition, said device including a tank providing a reservoir for said stock, a pipe line extending therefrom, a beater, said pipe line discharging into said beater, a valve in said pipe line at said beater, a valve in said line, a pump connected in said line between the last mentioned valve and said tank, providing the reservoir for said stock, said valves providing means for trapping stock in said line and maintaining said stock in a condition for circulation.
